UNITED STATES PATENT OFFICE

PETER J. WESOLOWSKI, OF DETROIT, MICHIGAN

WINDOW FASTENER

Application filed November 26, 1928. Serial No. 321,935.

This invention relates to window fasteners and more particularly to a combined fastener and latch construction including means for securing the window sections in relatively adjusted positions.

The invention has an object to simplify, render more efficient, and improve generally constructions of this type and these, as well as other objects, advantages, and the novel details of construction will be made more apparent as this description proceeds, especially when considered in connection with the accompanying drawings, wherein

Figure 1 is a fragmentary perspective view of a window with my invention attached thereto;

Figure 2 is a vertical sectional view through the device;

Figure 3 is a sectional elevation taken substantially on the plane indicated by line 3—3 in Figure 2; and

Figure 4 is a fragmentary elevational view of the link and its support.

Referring now particularly to the drawings wherein like reference characters indicate like parts, it will be noted that there is illustrated the adjacent rails 10 and 11 of two window sashes preferably of the vertical slidable type which are movable in the manner suggested in Figure 1 for opening the window and assume the position shown in Figure 2 when closed, that is with their rails 10 and 11 adjacent one another.

My improved window fastener consists essentially of a bracket 12 adapted to be secured to the rail 10 of one of the sashes, this bracket consisting of a base plate 13 and an upright portion 14. The bracket 12 has a dual function of constituting a support for the connecting link or arm 15 and of constituting a keeper plate for the locking element of the fastener.

The link or arm 15 is in the form of an elongated plate member provided with a longitudinally extending slot 16, the member 15 being also formed with a lateral ear at one end thereof through which is passed a rivet or stud 17 which also extends through the upright portion 14 of bracket 12 for pivotally securing link 15 thereto. The upright por-

tion 14 of bracket 12 is also provided with a cutaway portion forming a keeper slot or recess 18, the base 13 of the bracket being also preferably cut away as at 19 to facilitate the engaging of the locking element yet to be referred to. The slot 16 of link member 15 is provided with an enlargement 16' at the end thereof adjacent its pivotal connection to the bracket 12.

Mounted on the rail 11 of the other sash section is a complementary latch or fastener member indicated generally by the reference character 20. This member consists essentially of a base 21 and a housing 22. The base portion 21 provides means for attaching this fastener member to the rail 11, as for instance by means of screws or the like 23. Mounted in the housing portion 22 and extending therethrough is the shaft 24 of a locking element. One end of shaft 24 is provided with a head having an annular groove 25 and consisting further of an angular crank or arm 26 and a laterally bent end or projection 27. The other end of shaft 24 is provided with cam member 28 adapted for engagement with a cam surface 29 formed on the housing 22 and an operating handle 30. Surrounding the shaft 24 and arranged within the housing 22 is spring 31 which bears on the one hand against a wall of the housing and on the other hand against a shoulder 32 formed on shaft 24. This spring acts to normally project the head of the locking member outwardly from the housing 22.

In practice the head of the locking element extends through slot 16 of link 15 and when the grooved portion 25 is not in register with the enlargement 16' of the slot 16 the locking element is non-separably connected to link 15. By rotating the locking element the end or projection 27 thereof may be brought into engagement with the keeper recess 18 of bracket 14. This position of the parts is shown in Figures 2 and 3 and the sashes 10 and 11 are thus completely closed and locked against relative movement. Upon rotation of the locking member to disengage the projection 27 from the keeper recess 18 the sashes may be relatively moved and thus one of them opened a distance corresponding to the length 100

of slot 16 as will be obvious. When one of the sashes has been thus adjusted the sashes may be locked against further relative movement by rotating handle 30 of the locking element, whereby the arm 26 is brought to bear against link 15 so as to clamp the link between the head of the locking element and the housing 22. This clamping action results from the engagement of cam 28 with the 10 cam surface 29 on the housing, this cam action axially displacing shaft 24 against the action of spring 31 to thus clamp the link 15 in the manner above described.

The wall of housing 22 is formed with a 15 slot 33 through which the head of the locking element may be withdrawn by axially displacing shaft 24 against the action of spring 31. Thus if the link 15 is so moved as to position the slot 16 thereof parallel with slot 33 20 the two fastener members may be disconnected the enlargement 16' of the slot 16 permitting the withdrawal of the head of the locking element. With the fastening members thus disconnected the sashes can be opened 25 to the full extent provided for by their construction.

From the foregoing it will be immediately apparent that the above described window fastener not only constitutes means for positively locking the sash sections in completely closed position but also provides means for locking the sash sections in adjusted positions. It will be understood that in practice the link 15 will preferably be of a length 30 which will permit of a relative adjustment of the sash sections to open position a distance insufficient to permit the unauthorized entrance of a person through the window opening so that irrespective of the clamping action between the link and the complementary latch section 20 entrance through the window opening could not be gained by raising or lowering either of the sash sections. However, the sash sections may be raised or lowered and secured in their adjusted position by the clamping engagement of head of the locking element upon link 15 thereupon positively preventing any further relative movement 40 of the sash sections and also preventing any rattling of the sections. By disconnecting the fastener sections the sash sections may be opened as desired.

While the invention has been illustrated as employed in connection with sashes, it will 55 be obvious that it may be employed with equal facility in connection with various other closures, as for instance transoms and the like.

The construction of the several parts constituting my improved window fastener is such that they may be cheaply, quickly, and durably manufactured at a minimum cost and may be installed with facility without requiring the services of a skilled mechanic.

While one specific embodiment of the in-

vention has been illustrated and described in some detail, it will be immediately apparent that various modifications in the specific structure illustrated may be resorted to without departing from the spirit and scope of this invention, and to this end reservation is made to make such changes as may come within the purview of the accompanying claims.

What I claim as my invention is:

1. A fastener for windows having a pair of relatively movable sash sections comprising a bracket secured to one of the sash sections and provided with a keeper slot, a slotted link secured to said bracket, and a fastener section secured to the other sash section and including a rotary cam actuated locking element engageable in the slot in said link and permitting relative adjustment of the movable sashes, said locking element being operable to clamp said link or to engage said keeper slot.

2. A fastener for windows having a pair of relatively movable sash sections comprising a bracket secured to one of the sash sections and provided with a keeper slot, a slotted link secured to said bracket, and a fastener section secured to the other sash section, said latter fastener section comprising a support, a rotatable locking element engageable in the slot in said link and permitting relative adjustment of the movable sash sections, cooperating cam surfaces formed on said support and locking element for causing said locking element to clampingly engage said link for securing the sash sections in various open positions, said locking element also engaging said keeper slot for locking said sash sections in closed position.

3. A window fastener comprising two complementary sections secured respectively to movable sashes, one section comprising a bracket formed with a keeper recess and a slotted link pivotally connected to said bracket, the other section comprising a housing, a rotatable locking element supported by said housing and projecting through said slotted link, said housing and locking element being formed with cooperating cam surfaces for axially shifting said locking element, a spring for resisting said shifting movement, said locking element being shiftable for clamping the link between said element and housing, said element being also rotatable to engage said keeper recess.

4. A window fastener comprising two complementary sections secured respectively to movable sashes, one section comprising a bracket formed with a keeper recess and a slotted link pivotally connected to said bracket, the other section comprising a housing, a rotatable locking element supported by said housing and projecting through said slotted link, said housing and locking ele-

ment being formed with cooperating cam surfaces for axially shifting said locking element, a spring for resisting said shifting movement, said locking element being shift-
5 able for clamping the link between said ele-
ment and housing, said element being also
rotatable to engage said keeper recess, said
housing being formed with a slot through
which said locking element may be with-
10 drawn to disconnect said fastener sections.

5. A window fastener comprising a pair of sections secured respectively to movable sashes, one section including a bracket formed with a keeper recess, a slotted link
15 connected to said bracket, the other section comprising a supporting member, a rotatable locking element supported by said mem-
ber and projecting through said slotted link and permitting relative adjustment of the
20 window sashes, and cooperating means upon said supporting member and locking ele-
ment operable upon rotation of the latter for axially shifting said element to clamp said link between said element and supporting
25 member, said element being also rotatable to engage said keeper recess.

In testimony whereof I affix my signature.
PETER J. WESOLOWSKI.
